LIFTING DEVICE

Harvard K. Hecker, University City, Mo., assignor
to Curtis Mfg. Company, St. Louis, Mo., a corporation of Missouri

Application April 24, 1950; Serial No. 157,704

7 Claims. (Cl. 187—8.61)

1

This invention relates to improvements in lifting devices. More particularly, this invention relates to improvements in lifting devices which are normally concealed below the floors of buildings or structures.

It is therefore an object of the present invention to provide an improved lifting device which can normally be concealed below the floor of a building or structure.

It is frequently desirable to provide lifting devices that can be concealed below the floors of the buildings or structures in which those devices are to be operated. Such lifting devices can be concealed in pits below the floors until such time as they are needed to lift objects, and then those devices can be actuated to move upwardly above the level of the floors. When the lifting devices have performed their intended functions, they can again be returned to their positions in the pits below the level of the floors. Where this is done, it is possible for personnel to move about freely on the floors of the buildings or structures without any fear of tripping over the lifting devices. The pits for the lifting devices are customarily covered by movable doors which must be opened and closed whenever the lifting devices move upwardly or downwardly into or out of the pits. Where they are properly designed and constructed, the movable doors work quite well. However, if not properly designed and constructed the movable doors can jam and cause difficulty, and in any event the movable doors and their actuating mechanisms increase the cost of the lifting devices. The present invention obviates the cost of movable doors and the actuating equipment therefore, and yet fully protects personnel against any danger of falling into the pit for the lifting device by providing a number of supporting pads that are spaced apart from each other and from cover plates to permit passage of the lifting device therebetween, but that are spaced sufficiently close together and to the cover plates to keep a man's foot from entering the pit. The spaced supporting pads and cover plates thus provide the protection usually afforded by the movable doors, and yet they avoid the cost of such doors and the actuating equipment therefor. It is therefore an object of the present invention to provide supporting pads and cover plates which are spaced apart sufficiently to permit the passage of the lifting device therebetween but which are sufficiently close together to keep a man's foot from entering the pit.

The supporting pads and cover plates provide

5

a number of spaced openings between them, and those openings are complementary to the shape of the superstructure of the lifting device. That superstructure has spaced solid portions that fit neatly within the openings between the pads and cover plates, and it has spaced open portions that telescope neatly over the spaced pads. It is therefore an object of the present invention to provide supporting pads and cover plates that form openings complementary to the superstructure of a lifting device, and to provide a superstructure that has spaced solid portions neatly fitting the openings between the spaced pads and cover plates, and has spaced open portions neatly telescoping over those pads.

Made in this way, the superstructure of the present invention can provide a large supporting area to engage the object to be lifted, and yet that superstructure can be light in weight. Such a superstructure can easily accommodate vehicles with chassis of different designs.

Other and further objects and advantages of the present invention should become apparent from an examination of the drawing and accompanying description.

In the drawing Fig. 1 is a plan view of one form of cover plate, supporting pad, and superstructure provided by the present invention. 20 25 30 35 40 45

Fig. 2 is a side elevation view of the superstructure shown in Fig. 1.

Fig. 3 is a cross-sectional side view of the cover plate and supporting pads at the right hand end of Fig. 1.

Fig. 4 is a cross-sectional side view of the cover plate and supporting pads at the left hand end of Fig. 1, and it also shows the left hand end of the superstructure of Fig. 1.

Fig. 5 is a plan view of another form of cover plate, supporting pad, and superstructure provided by the present invention, and

Fig. 6 is a cross-sectional side view of the left hand cover plate, and supporting pads of Fig. 5, and it shows the left hand end of the superstructure of Fig. 5.

Referring to the drawing in detail, the numeral 10 denotes transversely-extending angles which will be intimately secured to the concrete or

2

other material that is used in forming the pit and the floor of the building or structure in which the lifting device is to be operated. The numeral 12 generally denotes longitudinally-extending angles, and these angles are welded or otherwise secured to the angles 10 to form a frame around the pit. The angles 10 are longer than the angles 12, but they are denominated as transversely-extending angles because they extend transversely of the axis of the vehicle to be supported by the lifting device.

The vertically-directed portions of the angles 10 and 12 will extend downwardly within the pit formed in the floor of the building or structure, and they can serve as guides to the cement finisher who smoothes the surface of the pit. The cement can be brought up to the lower edges of the vertically-directed portions of the angles 10 and 12; thus providing an even, unbroken surface around the interior of the pit. Similarly, the horizontally-directed portions of the angles 10 and 12 can serve as guides to the cement finisher who smoothes the floor of the building or structure. The cement can be brought up to the edges of the horizontally-extending portions, thus providing an even, unbroken surface for the floor.

The numeral 14 denotes cover plates which are disposed at the opposite ends of the pit. The cover plates 14 are identical, but one is rotated one hundred and eighty (180) degrees relative to the other about a vertical axis. One cover plate 14 overlies the left hand end of the pit while the other cover plate overlies the right hand end of the pit. Each of the cover plates 14 has a rectangular opening 16 adjacent the outer end thereof, and each cover plate has a slot 18 which is contiguous with the rectangular opening 16. The slots 18 extend from the openings 16 to the inner edges of the plates 14, and the slots 18 are at the longitudinal centers of the cover plates 14.

Each of the cover plates 14 is underlain by a sturdy frame 20; the frames 20 consisting of two transversely-extending side plates, a longitudinally-extending spacer which extends between and connects the outer ends of the side plates, and two longitudinally-extending ribs that are adjacent the inner ends of the side plates and that have their confronting faces spaced apart. The side plates are preferably secured to the spacers and the ribs by welding; the resulting welded structure being strong. The frames 20 are preferably secured to the cover plates 14 by welding. The frames 20 are secured to the under surfaces of the cover plates 14 adjacent the openings 16 in those cover plates; the confronting faces of the ribs of the frames 20 being adjacent the edges of slots 18. The side walls of the frames 20 have slots 22, 24 and 26 formed in them, and those slots open to the upper faces of those side plates. The slots 22, 24 and 26 extend vertically downwardly into the side plates of the frames 20; the slots 22 being the deepest, the slots 24 being of intermediate depth, and the slots 26 being the shallowest.

A large pad 28 is welded or otherwise secured to the side walls of the frames 20, and pads 30 and 32 of lesser size are welded or otherwise secured to the side walls of the frames 20. With such an arrangement, the frames 20 are secured to the cover plates 14 and hold the pads 28, 30 and 32 in precisely spaced relation relative to each other and relative to the cover plates 14. The pads and cover plates are dimensioned to provide a narrow opening all around the outer edges of each pad

and also to form an opening between that edge of pad 28 which confronts the two pads 30 and 32; the pads 30 and 32 forming a relatively wide opening between their confronting edges. The various openings will preferably range from one and one-eighth (1 1/8) to one and three-quarters (1 3/4) inches in width; such openings being small enough to keep a man's foot from passing through.

Legs 34, preferably of L-shape and preferably formed of angles, are secured to the under surface of each cover plate 14; two legs 34 being secured to each cover plate 14. The legs 34 have horizontally-disposed portions which underlie the inner ends of plates 14; those portions terminating adjacent the slots 18. The legs 34 have vertically-directed portions which extend downwardly from the cover plates 14 and rest on the bottom of the pit. These legs support the inner ends of the cover plates 14; the outer ends of those cover plates being supported by the angles 12 of the frame, as by overlying and being bolted to the angles 12. The support of the cover plates 14 is so firm and steady that automotive vehicles can be driven onto those cover plates.

Tabs 36 are secured to the under surfaces of the cover plates 14, and they extend inwardly beyond the inner edges of those plates. These tabs underlie and support the inner ends of movable doors 40 which are pivotally secured at their outer ends to the angles 10 by hinges 38. These doors are free to move upwardly away from the tabs 36 as the lifting device moves upwardly, and they will be held firmly against movement below the horizontal by the tabs 36. The cover plates 14

and the pads 28, 30 and 32 thus define a plane in which doors 40 normally lie. When the lifting device is down in the pit, the doors 40 coact with the cover plates 14 and the pads 28, 30 and 32 to provide a support strong enough to hold an automotive vehicle. When the lifting device moves upwardly, the doors 40 will open and lean against that device; returning to closed position, under the action of gravity, when the lifting device re-enters the pit.

The lifting device will usually include a hydraulic piston and the piston will usually carry a disc 44 at the top thereof. The disc 44 has a number of openings therethrough to receive bolts that can seat in the top of the piston. A supporting bar or yoke 42 is welded or otherwise secured to the top of the disc 44, and reinforcing plates 46 of generally triangular shape extend between the surface of disc 44 and the sides of the bar 42. Welding the supporting bar 42, the disc 44, and the reinforcing plates 46 together forms a strong, rigid support.

A longitudinally-extending plate 50 is secured to each end of the bar 42; those ends of bar 42 extending upwardly in a gentle curve. The plates 50 will preferably be secured to the bar 42 by welding. Transversely-extending plates 54 are secured to the opposite ends of the longitudinally-extending plates 50, and the outer ends of the plates 54 are connected together by longitudinally-extending plates 48. Longitudinal-extending plates 52 connect the inner ends of the transversely-extending plates 54 together. Reinforcing plates 53 extend between and are welded to the bar 42 and the plates 52.

The plates 48, 50, 52, 53 and 54 form reticules which are complementary to the interconnected openings between cover plates 14 and pads 28, 30 and 32 and between the pads 28, 30 and 32. As a result those reticules will pass neatly through those interconnected openings. The bar 42 will pass

through slots 18. The plates 48, 50, 52, 53 and 54 and the bar 42 are so dimensioned relative to the openings 16, slots 18, and pads 28, 30 and 32 that a clearance of from one-quarter ($\frac{1}{4}$) to three-eighths ($\frac{3}{8}$) of an inch is maintained between the stationary and movable parts of the lifting device.

As the superstructure of the lifting device moves upwardly, the bar 42 will engage the inner ends of the doors 40 and cause those doors to rotate around hinges 38. Those doors will then be held open by engagement with the sides of the piston, as by resting against the sides of that piston. When the superstructure moves downwardly the doors 40 will automatically close under the action of gravity when the superstructure moves out of engagement with them. With the exception of the doors 40, there are no moving parts in the covering for the pit. This provides full and adequate protection at low cost and with no risk of jamming of the operating mechanism.

In Figs. 5 and 6, the numeral 110 denotes transversely-extending angles which will be intimately secured to the concrete or other material that is used in forming the pit and the floor of the building or structure in which the lifting device is to be operated. The numeral 112 generally denotes longitudinally-extending angles, and these angles are welded or otherwise secured to the angles 110 to form a frame around the pit. The angles 110 are longer than the angles 112, but they are denominated as transversely-extending angles because they extend transversely of the axis of the vehicle to be supported by the lifting device.

The vertically-directed portions of the angles 110 and 112 will extend downwardly within the pit formed in the floor of the building or structure, and they can serve as guides to the cement finisher who smoothes the surface of the pit. The cement can be brought up to the lower edges of the vertically-directed portions of the angles 110 and 112, thus providing an even, unbroken surface around the interior of the pit. Similarly, the horizontally-directed portions of the angles 110 and 112 can serve as guides to the cement finisher who smoothes the floor of the building or structure. The cement can be brought up to the edges of the horizontally-extending portions, thus providing an even, unbroken surface for the floor.

The numeral 114 denotes cover plates which are disposed at the opposite ends of the pit. The cover plates 114 are identical, but one is rotated one hundred and eighty (180) degrees relative to the other about a vertical axis. One cover plate 114 overlies the left hand end of the pit while the other cover plate overlies the right hand end of the pit. Each of the cover plates 114 has a rectangular opening 116 adjacent the outer end thereof, and each cover plate has a slot 118 which is contiguous with the rectangular opening 116. The slots 118 extend from the openings 116 to the inner edges of the plates 114, and the slots 118 are at the longitudinal 65 centers of the cover plates 114.

Each of the cover plates 114 is underlain by a sturdy frame 120; the frames 120 consisting of two transversely-extending side plates, and a longitudinally-extending spacer which extends between and connects the outer ends of the side plates. In the embodiment shown, the side plates and the spacer are all part of the same piece; that piece being bent to form a U. The frames 120 are preferably secured to the cover plates 75

114 by welding and they are adjacent the openings 116 in those cover plates. The side walls of the frames 120 have slots 122, 124 and 126 formed in them; and those slots open to the upper faces of those side plates. The slots 122, 124 and 126 extend vertically downwardly into the side plates of the frames 120; the slots 122, 124 and 126 being of the same depth.

Four pads 128 are welded or otherwise secured to the side walls of the frames 120. With such an arrangement, the frames 120 are secured to the cover plates 114 and hold the pads 128 in precisely spaced relation relative to each other and relative to the cover plates 114. The pads and cover plates are dimensioned to provide a narrow opening all around the outer edges of each pad.

Legs 134, preferably of L-shape and preferably formed of angles, are secured to the under surface of each cover plate 114; two legs 134 being secured to each cover plate 114. The legs 134 have horizontally-disposed portions which underlie the inner ends of plates 114; those portions terminating adjacent the slots 118. The legs 134 have vertically-directed portions which extend downwardly from the cover plates 114 and rest on the bottom of the pit. These legs support the inner ends of the cover plates 114; the outer ends of those cover plates being supported by the angles 112 of the frame, as by overlying and being bolted to the angles 112. The support of the cover plates 114 is so firm and steady that automotive vehicles can be driven onto those cover plates. The legs 134 also underlie and support the inner ends of movable doors 140 which are pivotally secured at their outer ends to the angles 110 by hinges 138. These doors are free to move upwardly away from the legs 134 as the lifting device moves upwardly and they will be held firmly against movement below the horizontal by the legs 134. The cover plates 114 and the pads 128 thus define a plane in which doors 140 normally lie. When the lifting device is down in the pit, the doors 140 coact with the cover plates 114 and pads 128 to provide a support strong enough to hold an automotive vehicle. When the lifting device moves upwardly, the doors 140 will open and lean against that device; returning to closed position, under the action of gravity, when the lifting device re-enters the pit.

The lifting device will usually include a hydraulic piston and the piston will usually carry a disc 144 at the top thereof. The disc 144 has a number of openings therethrough to receive bolts that can seat in the top of the piston. A supporting bar or yoke 142 is welded or otherwise secured to the top of the disc 144, and reinforcing plates 146 of generally triangular shape extend between the surface of the disc 144 and the sides of the bar 142. Welding the supporting bar 142, the disc 144, and the reinforcing plates 146 together forms a strong, rigid support.

A longitudinally-extending plate 150 is secured to each end of the bar 142; those ends of bar 142 extending vertically upward. The plates 150 will have slots in their lower center portions that can telescope over those ends of bar 142. Plates 150 are preferably secured to the bar 142 by welding. Transversely-extending plates 154 are secured to the opposite ends of the longitudinally-extending plates 150, and the outer ends of the plates 154 are connected together by longitudinally-extending plates 148. Longitudinally-ex-

tending plates 152 connect the inner ends of the transversely-extending plates 154 together. Saw-toothed vehicle-engaging plates 156 will be riveted to the plates 148, 150, and 152, and the plates 156 will extend above the plates 148, 150, and 152.

The plates 148, 150, 152 and 154 form reticules which are complementary to the interconnected openings between cover plates 114 and pads 128 and between the pads 128. As a result those reticules will pass neatly through those interconnected openings. The bar 142 will pass through slots 118.

As the superstructure of the lifting device moves upwardly, the bar 142 will engage the inner ends of the doors 140 and cause those doors to rotate around hinges 138. Those doors will then be held open by engagement with the sides of the piston, as by resting against the sides of that piston. When the superstructure moves downwardly the doors 140 will automatically close under the action of gravity when the superstructure moves out of engagement with them. With the exception of the doors 140, there are no moving parts in the covering for the pit. This provides full and adequate protection at low cost and with no risk of jamming of the operating mechanism.

Whereas a preferred embodiment of the present invention has been shown and described in the drawing and accompanying description it should be obvious to those skilled in the art that various changes may be made in the form of the invention without affecting the scope thereof.

What I claim is:

1. In a lifting device that has a superstructure and that is adapted to be positioned in a pit in the floor of a building but is actuatable to rise upwardly out of said pit and to extend above the level of that floor, a covering for said pit which comprises a cover plate, an opening in said plate, a slot contiguous with said opening, a frame that is secured to the underside of said plate and extends under said opening, and supporting pads supported by said frame, said supporting pads being disposed within said opening but being spaced from each other and from the edges of said opening to provide interconnected openings which can permit ready passage of one portion of the superstructure of said lifting device therethrough but which will resist passage therethrough of a man's foot, said supporting pads being substantially co-planar with said cover plate, said slot preventing the passage of a man's foot therethrough but permitting passage of another portion of the superstructure of the lifting device therethrough, said one portion of said superstructure being a reticule complementary to the said interconnected openings between said pads and between said pads and the edges of said opening, said other portion of said superstructure of said lifting device being a transversely-extending bar.

2. In a lifting device that has a superstructure and that is adapted to be positioned in a pit in the floor of a building but is actuatable to rise upwardly out of said pit and to extend above the level of that floor, a covering for said pit which comprises a cover plate, an opening in said plate, a frame that is secured to the underside of said plate and extends under said opening, and a supporting pad supported by said frame, said supporting pad being disposed within said opening but being spaced from the edges of said opening to provide interconnected openings

which can permit ready passage of the superstructure of said lifting device therethrough but which will resist passage therethrough of a man's foot, said supporting pad being substantially co-planar with said cover plate, the outer end of said plate overlying and being supported by the floor of said building and the inner end of said plate having a downwardly depending portion extending to the bottom of said pit and resting thereon.

3. In a lifting device that has a superstructure and that is adapted to be positioned in a pit in the floor of a building but is actuatable to rise upwardly out of that pit and to extend above the level of that floor, a covering for said pit which comprises a cover plate, an opening in said plate, a frame that is secured to the underside of said plate and extends under said opening, a supporting pad supported by said frame, and a leg depending downwardly from said cover plate and resting on the bottom of said pit to support one portion of said cover plate, said supporting pad being spaced from the edges of said opening to provide interconnected openings small enough to prevent the passage of a man's foot therethrough but large enough to permit the passage of the superstructure of said lifting device therethrough, said supporting pad being substantially co-planar with said cover plate, said leg being spaced from the path of movement of said superstructure of said lifting device.

4. In a lifting device that has a superstructure and that is adapted to be positioned in a pit in the floor of a building but is actuatable to rise upwardly out of that pit and to extend above the level of that floor, a covering for said pit which comprises a cover plate, an opening in said cover plate, a frame that is secured to the underside of said cover plate and extends under said opening, and a supporting pad supported by said frame, said supporting pad being disposed within said opening but being spaced from the edges of said opening to provide interconnected openings which can permit ready passage of one portion of the superstructure of said lifting device therethrough but which will resist passage therethrough of a man's foot, said supporting pad being substantially co-planar with said cover plate, said one portion of said superstructure being a reticule complementary to the said interconnected openings between said pad and the edges of said opening, said reticule including transversely-extending plates and longitudinally-extending plates.

5. In a lifting device that has a superstructure and that is adapted to be positioned in a pit in the floor of a building but is actuatable to rise upwardly out of that pit and to extend above the level of that floor, a covering for said pit which comprises a cover plate, an opening in said plate, a frame that is secured to the underside of said plate and extends under said opening, and a supporting pad supported by said frame, said supporting pad being disposed within said opening but being spaced from the edges of said opening to provide interconnected openings which can permit ready passage of one portion of the superstructure of said lifting device therethrough but which will resist passage therethrough of a man's foot, said one portion of said superstructure being a reticule complementary to the said interconnected openings between said pad and the edges of said opening, said reticule including transversely-extending plates and longitudinally-extending plates, said frame having

slots therein to receive said longitudinally-extending plates of said reticule.

6. In a lifting device that has a superstructure and that is adapted to be positioned in a pit in the floor of a building but is actuatable to rise upwardly out of said pit and to extend above the level of that floor, a covering for said pit which comprises a cover plate, an opening in said cover plate, a slot contiguous with said opening, a frame that is secured to the underside of said cover plate and extends under said opening, and supporting pads supported by said frame, said supporting pads being disposed within said opening but being spaced from each other and from the edges of said opening to provide interconnected openings which can permit ready passage of one portion of the superstructure of said lifting device therethrough but which will resist passage therethrough of a man's foot, said slot preventing the passage of a man's foot therethrough but permitting passage of another portion of the superstructure of the lifting device therethrough, said one portion of said superstructure being a reticule complementary to the said interconnected openings between said pads and between said pads and the edges of said opening, said other portion of said superstructure of said lifting device being a transversely-extending bar, said frame having transversely-extending side plates to support said supporting pads, the ends of said side plates being spaced apart to permit passage therebetween of said transversely-extending bar.

7. In a lifting device that has a superstructure and that is adapted to be positioned in a pit in the floor of a building but is actuatable to rise upwardly out of that pit and to extend above the level of that floor, a covering for said pit which comprises a cover plate, an opening in said plate, a frame that is secured to the underside of said plate and extends under said opening, and a supporting pad supported by said frame, said supporting pad being disposed within said opening but being spaced from the edges of said opening to provide interconnected openings which can permit ready passage of one portion of the superstructure of said lifting device therethrough but which will resist passage therethrough of a man's foot, said supporting pad being substantially coplanar with said cover plate, said one portion of said superstructure being a reticule complementary to said interconnected openings, said one portion of said superstructure having toothed surfaces at the top thereof to engage and hold the object to be lifted.
